CLAIM

We claim the ornamental design for table clamp for electronic display mount, as shown.

DESCRIPTION

FIG. 1 is a front perspective view of a table clamp for electronic display mount according to an embodiment of the invention;

FIG. 2 is a side elevation view of a first side thereof;

FIG. 3 is a side elevation view of a second side thereof;

FIG. 4 is a front elevation view thereof;

FIG. 5 is a rear elevation view thereof;

FIG. 6 is a bottom plan view thereof; and,

FIG. 7 is a top plan view thereof.

The broken line showing of parts of the drawings is included for the purpose of illustrating use and environment and forms no part of the claimed design.
